UNITED STATES PATENT OFFICE.

EDWARD W. BRAY, OF NORFOLK, VIRGINIA.

WATER-CIRCULATOR FOR STEAM-BOILERS.

1,139,334.

Specification of Letters Patent. Patented May 11, 1915.

Application filed November 6, 1913. Serial No. 799,561.

To all whom it may concern:

Be it known that I, EDWARD W. BRAY, a citizen of the United States, residing at Norfolk, in the county of Norfolk and State of Virginia, have invented certain new and useful Improvements in Water-Circulators for Steam-Boilers, of which the following is a specification.

This invention relates to improvements in water circulators for steam boilers, and particularly to a means whereby the heating and water space is divided at or near the combustion chamber.

The object of the invention is to provide means whereby the heating surface may be so divided as to use the same for causing the water to circulate from the after or furnace door end of the boiler in the bottom, to the forward or combustion chamber end of the boiler, and up around the combustion chamber to the water line, thence to the after end of the boiler where it cools and drops toward the bottom, thus creating a continuous circulation.

My invention is designed to accomplish these features by the use of novel and original means fully described herein, and illustrated by the drawings. Such parts as are not pertinent to my invention, have been omitted from the drawings.

Figure 1, is a side elevation of a double furnace boiler, the shell broken away so as to show the furnace, baffle plate and pipe. Fig. 2, is a section taken at y—y of Fig. 1.

Similar reference characters refer to similar parts.

Figs. 1, and 2, show one form of my invention embodied in a double furnace boiler, in which I provide a baffle plate 1, at the tube or flue sheet end of the combustion chamber, the said plate being secured to, and radiating from the combustion chamber to the shell of the boiler, and secured thereto by suitable means 2. The baffle plate 1, in this form of construction, is preferably in four sections, though I am not confined to any number of sections, but may vary the number according to requirements. The baffle plate 1, is provided near the shell 3, with apertures 4, for the purpose hereinafter explained in the operation of my invention. In Fig. 1, I also show a pipe 5, located near the shell 3, extending from the baffle plate 1, lying parallel with the furnace 6, the said pipe being provided with apertures 7, as will

be also hereinafter explained in the operation.

Having fully described a form of embodiment of my invention, I will proceed to describe its operation.

As soon as the fires are lighted in the furnace 6, the heated gases pass to the combustion chamber and are consumed, transmitting their heat by contact and radiation to the front head of the combustion chamber 65 and wrapper sheet 8. They being surrounded and in direct contact with the water, impart heat to the surrounding water which at once begins to expand, causing its gravity to lessen, thereby naturally forcing the water upward by the body of water lying on the bottom of the boiler under the furnaces, which will flow through the apertures 4, in the baffle plate 1, and the apertures 7, in the pipe 5, and as this water is heated, 70 continues to ascend, and will flow over the combustion chamber top in the direction of the after or furnace door end of the boiler, which is the coolest of the heating surfaces of the boiler, and then as its gravity increases, will begin to flow to the bottom due to its increased gravity, thus completing the cycle as indicated by the arrows.

It will be readily understood that a great variety of modifications may be made in details of construction, and arrangement of parts, due to the varied types of boilers and their arrangement of furnaces, without departing from the spirit of my invention, and not being aware of any device using a 80 baffle plate radiating from the combustion chamber to the shell of the boiler for this purpose, I therefore claim broadly, this feature.

Having thus fully described my invention, 95 what I claim as new, and desire to secure by Letters Patent of the United States, is—

1. In a steam boiler and water circulator therefor, the combination with a furnace and combustion chamber, of means provided 100 with an aperture radiating from said combustion chamber to the shell of the boiler, for the purpose specified.

2. In a steam boiler and water circulator therefor, the combination of a furnace and combustion chamber, and means provided with an aperture extending from the combustion chamber to the shell of the boiler for dividing the water space and heating surface at or near the back tube and flue 110

sheet at the combustion chamber end of the boiler, for the purpose specified.

3. In a circulator for steam boilers, the combination with a furnace and combustion chamber, of a baffle plate radiating from the combustion chamber to the shell of the boiler, and means in said baffle plate through which the water circulates from under the furnace and combustion chamber, up around

the sides and back thereof to the water line.

Signed at Norfolk, in the county of Norfolk, and State of Virginia, this 5th day of November, A. D. 1913.

EDWARD W. BRAY.
